UNITED STATES PATENT OFFICE.

WILLIAM W. LASKER, OF BROOKLYN, NEW YORK, ASSIGNOR TO POWERS ACCOUNTING MACHINE COMPANY, OF NEW YORK, N. Y., A CORPORATION OF DELAWARE.

TRANSFER OR CARRY-OVER MECHANISM.

1,391,959.

Specification of Letters Patent. Patented Sept. 27, 1921.

Application filed April 3, 1918. Serial No. 226,493.

To all whom it may concern:

Be it known that I, WILLIAM W. LASKER, a citizen of the United States, residing in Brooklyn, in the county of Kings and State 5 of New York, have invented certain new and useful Improvements in Transfer or Carry-Over Mechanism, of which the following is a specification.

This invention relates to a printing tabulator of the kind adapted to be controlled by perforated cards, and relates more particularly to matter divided from my copending application Serial No. 158,142, filed March 28, 1917, for printing tabulators.

15 The invention herein described relates particularly to the transfer or carry-over mechanism of said printing tabulator; and, therefore, only as much of the printing tabulator is described herein as is necessary to show 20 the connection between the matter of the original application and the matter divided out and claimed herein.

While herein and in said application minute details of one of many possible embodiments of the invention are described, the invention is not limited to these since various changes may be made in the details of construction and combination without departing from the spirit and scope of the invention as 30 claimed.

One object of the invention is to improve generally apparatus of this kind.

Another object of the present improvement is to construct a printing tabulator 35 having a novel form of carry over mechanism for the accumulating elements of the machine.

Still further objects and advantages of the present improvement will be set forth in the 40 following description and drawings in which,

Figure 1 is a side elevation of the printing and calculating mechanism constituting a part of the printing tabulator.

45 Fig. 2 is an interior side elevation partly in section of the type setting and calculating elements.

Fig. 3 is a detailed side elevation partly in section of the carry-over mechanism of the 50 accumulator mechanism.

Fig. 4 is a top plan view of Fig. 3.

Fig. 5 is a vertical section view taken on the line 5—5 of Fig. 3.

Fig. 6 is a perspective view of the means

for reciprocating the accumulator carriage 55 by two different actions for accumulating or total taking.

Fig. 7 is a fragmental longitudinal sectional view partly in side elevation of the type setting, calculating and carrying elements and showing the parts thereof in normal or initial position.

Fig. 8 is a similar view showing said elements in total taking position.

Fig. 9 is a fragmentary side elevation 65 partly in section showing the type setting actuating elements and restoring means.

Fig. 10 is a detail perspective view of one of the bell crank controls for the reciprocating actuating rack bars. 70

The invention herein relates to a printing tabulator which is adapted to be actuated by perforated cards, which in their passage through the machine operate elements for setting up type commensurate with the 75 designations on the card and actuate an accumulating mechanism for accumulating therein the data recorded on the card perforations whereby the total accumulated data may be computed and then printed by the 80 printing elements of the machine.

The embodiment illustrated in said co-pending application comprises a main frame, the card feeding mechanism, the card analyzing mechanism, and an upper base 10 85 (Fig. 1) on which the accumulating and printing mechanism 12 hereinafter to be described and the paper carriage 13 are mounted.

The cards to be analyzed are disposed in a 90 receptacle and are fed to the analyzing mechanism in which, as shown in said co-pending application, analyzing pins, which find perforations in the cards being analyzed, pass upwardly therethrough and engage extension pins, which in turn actuate registering stop 14. After the cards have been analyzed they are discharged into a suitable receptacle.

The first step in the operation of the type 100 setting tabulating mechanism, consists in the pushing up of the various stop pins 14 (Fig. 2) by means of the extension pins, which are actuated by the various perforations in the cards as they pass through the machine. A 105 specific description of the stop pins, their supporting means, and the means for returning them to normal position after they

have set in motion various other parts of the type setting and tabulating mechanism is given in said copending application.

The registering stops 14 correspond in number to the extension pins except that there are no extension pins or registering stops 14 to correspond with the analyzing pins that analyze the zero perforations in the cards. Each row of registering stops 14 have a zero stop 16 associated therewith, which is normally in zero stopping position and will remain so unless one of the registering stops 1 to 9 inclusive associated therewith is actuated and therefore it is unnecessary for a zero analyzing pin to actuate or cooperate with a zero stop 16.

Herein the part of the accounting machine to the left of Fig. 2 will be considered the forward part of the machine, while that to the right of Fig. 2 will be considered the rear of the accounting machine.

The registering stops 14 in the present instance are arranged in a suitable number of rows having ten stops in each row, the stops of each row corresponding to the integers 9 to 1 inclusive and zero, the stop 9 being at the forward end of the machine and the zero stop at the rear end thereof. The stops 14 corresponding to the integers 1 to 9 inclusive are each composed of a flat body portion comprising a head having forwardly projecting portion 17 a cam face 18 facing forward directly above said projection 17, a small rectangular shaped abutment 19 made on one side of the pin and adjacent its upper end, and a lower restoring notch 21 on the rear edge thereof. The stops 14 have their projections 17 normally resting on an upper stop plate 22 and extend down through a lower stop plate 23. The stop plates 22 and 23 have openings therein corresponding in number to the stops 14 and zero stop 16 in registry with each other whereby the pins may reciprocate through them. The stop plates 22 and 23 are indirectly supported on the cheek plates 34.

The zero stops 16 are formed somewhat similar to the stops 14 and have a forward projection 36 at their upper end and a cam face 37 on the forward edge extending upward from the extension 36 and a recess 38 in its rear edge.

Means is provided for anchoring the various registering stops 14 that are actuated by the extension pins and also holding the zero stops 16 in position for causing an actuation of the corresponding type setting and tabulating elements. This anchoring means is fully shown and described in said copending application and is not claimed herein. The zero stops 16 are normally disposed in raised position and whenever a stop 14 is actuated to the raised position,

simultaneously therewith the zero stop 16 in that row will be lowered. In order to accomplish this result an elongated lever 62 (Fig. 2) is provided for each row of stops 14, which lever is provided with a plurality of lugs 63 arranged in a straight line and all extending in the same direction, each lug 63 also extending into one of the recesses 21 of the stop pins 14. The front ends of the levers 62 are pivoted on a suitable shaft which is supported within the cheek plates 34 of the machine. The rear ends of the lever 62 are provided with lugs 66 which are slidably and pivotally mounted in slots 67 at the rear ends of the links 68, which links are pivoted on a shaft 69 supported by the cheek plates 34. The front end of the links 68 are provided with lugs 70 which are arranged to slide within a recess 38 formed in the rear edge of the naught stop 16.

Supported by the cheek plates 34 is a comb plate 71 the upper end of which is slotted to permit the lever 62 to extend therethrough and be guided thereby. A coil spring 71' is strained between the abutment 66 and the lower edge of the said plate 71 for the purpose of normally raising the naught stops 16 into the position shown in Fig. 2. Attention is called to the fact that when one of the stops 14 is raised, the actuation of the lever 62 by means of the cooperation of the slot 21, carried by the stop, with the plug 63, carried by the lever, will cause the link 68 to be actuated which will in turn lower the stop 16 of the row in which the stop pin 14 has been raised.

As has been heretofore described the first action that takes place when the machine is started, is the raising of the various stop pins 14 by the actuation of the extension pins which are in turn controlled by the perforations in the cards passed through the machine. After a card has transferred its data to the pins 14 by raising them, and has passed from the machine, means is provided for returning the pins 14 to their normal lower position for actuation by the next incoming card. This means for returning the stop pins to their normal position is described in detail in said copending application.

A lever 72 is provided having a bifurcated lower end 73 which straddles the main drive shaft 74 which provides the driving means, for the entire type setting and calculating mechanism. This lever 72 is provided with a pin 74 upon which is rotatably mounted a roller 75 which is arranged to roll within a cam slot 76 of a cam 77.

There is provided and described in said copending application, though not shown or claimed herein, a means operatively connected with said lever 72 whereby the stops 14 which have been set by the perforated

cards, are released by the aforementioned anchoring means after they have performed their functions.

As soon as the pins 14 are freed, the lever 62 will be pulled down by means of the coil spring 71', and in its downward movement the lugs 63 carried thereby will engage the slots 21 of the stop pins 14 and pull them downward to their normal lowered position.

10 The naught stop pins 16 are arranged, as shown in Fig. 7, to normally retain or hold back reciprocating rack bars, which during their reciprocation actuate type setting elements. As heretofore described, the raising 15 of a stop pin will lower the naught stop so that upon the actuation of a stop pin, the reciprocating rack bar associated therewith will be released and be permitted to run forward until it engages a raised stop pin 14. During their reciprocation the reciprocation 20 members have actuated the type setting elements and upon being stopped by the raised stop pins will hold the type setting elements in a position to set type corresponding 25 with the number of the raised stop pins. A detailed description of the reciprocating rack bars and their connection and coöperation with the naught stops, stop pins and type setting elements will now be 30 described.

The reciprocating rack bars each comprise a relatively thin bar shaped body portion 82 which is provided with a longitudinal slot 83 that is adapted to slide along a transverse bar 84, secured to the cheek plates 34. A transverse bar 85 is also provided which serves as a support for the forward end of the bar 82. The bar 85 is rigidly fastened to the cheek plates 34. A second 40 relatively thin bar shaped member 86 is pivoted at its front end to a pivot 87 carried by the front end of the bar 82. The upper edge of the bar 86 is provided with a recess 88 to receive a bar 89 which is reciprocated 45 by means hereinafter to be described, and during its reciprocation will move both the bar 82 and the bar 86 connected thereto. The bar 86 is provided with a cut away portion 90 so as to lessen the depth of the said 50 bar to enable it to slide above the shaft 82 and at the same time permit the outer ends of the bars 82 and 86 to remain parallel with each other. A spring 91 is strained between the free end of the bar 82 and a vertically extending arm 92 which is made integral with the inner end of the bar 82.

The free end of the bar 86 is provided with an off-set portion 93 which is adapted to extend through a slot 94 in the upper 60 edge of the bar 82 so that the extreme end 95 of the bar 86 may engage the bar 82 on its opposite side. Due to this arrangement the two bars 82 and 86 are always held together and as the bar 86 swings on its pivot

87 the end 95 of the bar 86 will engage and 65 slide up and down against the vertically extending arm 92 carried by the bar 82. A horizontally extending pin 96 is carried by one side face of the bar 82 which is adjacent to the bar 86 and pivotally mounted upon 70 which is a bell crank lever 97 (Fig. 10), the outer end of which is provided with a horizontally extending pin 98 which is reciprocatively movable in a slot 99 made in the bar 86. The other end of the lever 97 75 is provided with a lug 100 having a cam front face 101 and a right angular notch 102, in its rear edge, the horizontal wall of which is extended out at right angles to the lever 97 forming a rest 103 (Fig. 2). The 80 upper edge of the bar 82 is provided with an upstanding abutment 104 having a vertical front wall or inwardly turned shoulder 105, and an inclined or cam rear wall 106, the purpose of which inclined wall will be 85 hereinafter set forth. The bottom edge of the bar 82 is provided with an abutment 104' similar but smaller than the abutment 104 carried by its upper edge. This abutment 104' is provided with a vertical front 90 wall 105' directly beneath and in the same plane with the vertical wall 105 of the abutment 104. The abutment 104' is also provided with an inclined or cam rear wall 106' the purpose of which will be herein- 95 after set forth.

The bar 89 which as heretofore described, is for the purpose of reciprocating the bars 82 and 86 is itself reciprocated in the following manner, reference especially 100 being made to Fig. 1.

The bar 89 which is rectangular in cross section is rigidly connected at each end to a slide 107, which is reciprocatable between rollers 108 forming guideways therefor. A slot 109 is made in each cheek plate 34 which receive a roller 110 revolvably mounted on the shaft 111 secured to the rear end of the said slides 107. The front end of the slides 107 are provided with horizontally extending pins 112, which are reciprocatably mounted in slots 113 formed in the upper ends of levers 114, the lower portion of which are triangularly shaped, one corner being pivoted to stud shafts 115 carried by each 110 cheek plate 34. The other corner of the triangular shaped levers 114 carries a roller 116 which is arranged to roll within a suitable cam groove in a cam carried on the shaft 74. 115

Returning now to the reciprocating bars 120 82, the top edge of the forward portion of the said bars 82 are provided with gear teeth 119 which are in mesh with a gear 120 (Fig. 2) secured to type segments 121, which have bearing on a transverse shaft 122 carried between the cheek plates which segments have an arc shaped rear edge provided with gear teeth 123 which will here- 125

after be described. The front edge of the segments 121 are also made arc shaped and are provided with rectangular notches to receive the upturned ends of type 126. The 5 rear ends of the type are also provided with an upstanding portion 127 which is arranged to fit within rectangular openings radially back of said rectangular notches. A flat arch shaped plate 128 is arranged to fit 10 against the type 126 and to hold their upturned portions in engagement with said notches and openings respectively. The plates 128 are secured to the segment by means of bolts 129. Reading from the upper 15 edge of the type carrying portion of the segment, the type carried thereby read in sequence, the first type being zero, the next "1," the next "2," etc., the last type on the segment being numbered 9.

20 A description of the operation of the stop pins, the reciprocating rack bars and the oscillating type segments will now be given. In the position shown in Fig. 2 all of the stop pins 14 are down and all of the naught 25 stops 16 are in raised position. When the stop pins 14 are in their initial raised position the vertical walls 105' of the abutment 104' fit within the notches 38 in the upper end of the naught stops and consequently 30 hold the bars 82 and their associated bars 86 in their extreme rearward position, and also retain all of the type segments in a position to print ciphers. Although each spring 35 91 is exerting tension to lift the bar 86 nevertheless this bar is held to the limit of its downward movement due to the fact that the rest 103 carried by one end of the bell crank lever 97 will rest on top of the naught stop 16 (Fig. 7) which holds the said bell 40 crank 97 at the limit of its downward movement by means of the pin 98 carried by the member 82 and the slot 99 in the bar 86. As soon as any of the stop pins 14 are raised by means of said pin extensions, actuated by 45 means of a card passing through the machine, the naught stop 16 in that row is lowered simultaneously, as has been heretofore explained. The downward movement of the naught stop 16 frees the abutment 50 104' permitting the bar 82 to be carried forward. Simultaneously with the disengagement of the abutment 104' and the stop pin 16, the lever 86 is raised by means of the spring 91 which in its upward movement 55 moves the notch 88 to fit against the front side of the reciprocating bar 89. Attention is called to the fact that when the parts are in their normal position, the bar 89 is at the limit of its rearward movement and rests 60 against the vertical wall 105 of the abutment 104. As soon as the notch 88 engages the reciprocating bar 89, the said bar is locked between it and said vertical wall so that when the said bar 89 is reciprocated by 65 means of the lever 114 and its associated

parts, heretofore described, the bars 82 and 86 will also be moved forward. Simultaneous with the forward movement of the bar 86 the bell crank 97 is moved down. As the bar 89 is reciprocated by the lever 114, the 70 said bars 82 and 86 will be carried with it until the cam face 101 of the bell crank engages the rectangular abutment 19 of the stop pin 14 which has been raised. This contact lifts the bell crank 97, lowers the rod 86 75 against the tension of the spring 91 which in its downward movement releases the reciprocating bar 89. As soon as the bell crank 97 has been raised the vertical wall 105' of the abutment 104' will engage the 80 rear end of the raised stop pin 14 and prevent the bar 82 from moving further. Since the reciprocating bar 89 is released as the bar 82 is stopped, the bar 89 will continue its forward movement although the bar 82 85 and the lever 86 have been stopped. This is for the purpose of freeing the bars 82 and 86 from the reciprocating member 89 as they engage the stop pins in their forward position and thereby permitting the bar 89 to 90 carry all of the bars 86 forward which have not been freed therefrom in the manner heretofore described.

Due to the rack teeth 119, as the bar 82 is moved forward, the type segment 122 is 95 oscillated through the medium of the gear wheel 120 as heretofore described.

After all of the type segments have been set by the stop pins in position to print data transferred thereto from the cards, means is 100 provided for locking and alining the type segments so that they may not move during the printing operation. This locking and alining means will now be briefly described.

The extreme upper end of the lever 72 is 105 provided with a knife shaped transversely extending arm 130 slidably mounted within a slot 131, within the cheek plates 34. Both the slot 131 and the knife shaped member 130 which is herein termed a detent, are arranged radial to the gear teeth 123 of the type segments and lock the said segments 110 from moving, and line up the type carried thereby.

The locking of the printing segments and 115 the releasing of the stops 14, is brought about simultaneously so that the reciprocating members may be free to be moved back to their original position after printing without engaging any stop pins whatever except the 120 naught stops 16 as will be hereinafter more fully described.

A mechanism is herein provided for preventing all of the ciphers to the left of the digit last set up by the stop pin from being 125 printed. Or in other words, a mechanism is provided for retracting all of the segments out of printing position which have been left against the naught stops as the released bars 82 start on their forward movement.

Relatively thin levers 132 are provided which have on their upper edges an abutment 133 provided with a front cam wall 134 and a rear cam wall 135. The said rear cam wall is adapted to engage a cam wall 136 formed on the bottom edge of the reciprocatable bar 82 when the rack bars are retracted beyond zero printing position. The levers 132 are pivotally mounted upon a transverse shaft 137 which is reciprocatably mounted within slots 138 made in the cheek plates 34. Means is provided for reciprocating the shaft 137 and this means comprises bell cranks 139 each having a bifurcated upper end which straddle the pin 137. The bell cranks 138 are pivoted to a shaft 140 rigidly mounted in the cheek plates 34 and each has on its outer end a rigid horizontally extending pin 141 which fits within the bifurcated end of a lever 143 (Fig. 1) which lever is pivotally mounted upon a stud rigidly mounted in the cheek plates 34. The other end of the lever 143 is provided with a roller which runs in a suitable cam groove. The outer end of each lever 143 carries a lip 156 which extends horizontally to the right of the lever 143 a sufficient distance to engage the adjacent bar 132 of the next lower order. A spring 157 is strained between a bar 152 fastened between the cheek plates 34 and a downwardly extending ear 159 made integral with the lower edge of the bar 149. This spring is for the purpose of normally holding the levers 132 and 149 in such a position that the rear cam wall 135 will engage the cam face 136 of the rack bar when the rack bar is retracted beyond zero-printing position.

The operation of this mechanism will now be described. As the various stop pins 14 are elevated, and the associated stop pins 16 are lowered, as has been heretofore described, the bars 82 are started on their forward stroke. As they move forwardly the cam face 136 on the bottom edge of the rack bar 82 will strike the cam face 133 of the lever 132 and force it downwardly in the position shown in Fig. 2. The downward movement of the lever 132 will elevate the lever 149 which, through the medium of the horizontally extending lip 156 fastened thereto, will engage the adjacent lever 132 to the right thereof and force it down. As these levers 132 are forced down they will clear the bottom edge of the levers 82. After all of the bars 82, which have been controlled by the stops 14, have started on their forward movement and have forced down all of the levers 132 associated to the right thereof, the bell crank 139 is moved in a clockwise direction by means of the roller 145, cam groove 146, and its other intermediate associated elements. This movement of the bell crank 139 will reciprocate all of the bars 132; but those which have already been depressed by the forward movement of the bars 82 will slide beneath the said bars 82 and upon a rod 160 mounted between the cheek plates 34, engaging a longitudinal slot 161 made in the inner end of the bar 132. 70 However, those bars 132, which have not been depressed either by a movement of the bar 82 or by a lip 156 carried by the adjacent bar 149, will still be in their upward position as mentioned above, in which the cam face 135 lies adjacent to the cam face 136 of the reciprocatable bar 82. As a consequence, when these last mentioned levers 132 are moved by the bell crank 139 a longitudinal slot 162 made in the inner end of the lever 133 will receive the bar 160 and prevent the lever 132 from being depressed. As the bars 132 move farther under the action of the bell crank 139, the cam face 135 will engage the cam face 136 and force it 75 backwardly. The cam groove 146 is of such contour that the bell crank 139 will move the bars 82 back one space, so that the type segments associated therewith will occupy a position as shown in Fig. 1, in which the 80 naught type are below the printing position. As a consequence, when the bars 82 have finished their forward movement and are set up for printing, all of the type segments to the left of any type segment which is controlled by a stop pin 14 will be kicked back by the mechanism above described so that they will be in a non-print position. 85 Up to this point the general operation of the mechanisms thus far described, is as follows: When any of the stop pins 14 corresponding to the perforations in the cards fed through the machine, are raised, the naught stops in that row are simultaneously lowered which will permit the members 82 100 to move forward. The forward movement of the bars 82 rocks the lever 132 in an anti-clockwise direction, and all of the levers 132 of a lower order will also be rocked through the instrumentality of the lips 156, but all 105 of the bars 82, of an order higher than the rack bar of the highest order that is permitted by the removal of the naught stop and the setting of the pin 14 to be moved forwardly will be kicked back one space so 110 that the type sectors are oscillated down out of printing position. The bars 82, which have been moved forward come to rest the reciprocating bar 89 is freed and moves forward to the limit of its stroke. When all of 115 the type sectors are in position to print, the detent mechanism is operated, which slides the detent 130 into the gear teeth 123 of the type segments and locks them against movement. Simultaneously with the operation 120 of the detent mechanism, the release mechanism releases the stop pins 14 and permits them to be drawn down into their original position by means of the bar 62 which at the same time raises the naught stops 16. The 125 130

- paper carriage 13 is then, as will be explained, moved up into engagement with the type on the type segments, and the printing operation takes place. The printing carriage is then retracted, and at the same time means is provided for lowering the bars 86 so as to raise the bell cranks 97 so that when the bars reach the limit of the rearward stroke the rest 103 will be in position to rest
- 10 upon the top of the naught stops which are in their raised position as shown in Fig. 3. The means for lowering the bars 86 and lifting the bell cranks comprises a transverse bar 163 (Fig. 2) which is arranged
- 15 above the upper edge of the bars 86 being rigidly carried by the upper ends of slide levers 164 arranged adjacent the inner face of each cheek plate 34, which during their downward movement, slide the bar 163 in
- 20 slots 165 made in the said cheek plates. The slots 165 are of a length sufficient to permit the bar 163 to move down in contact with the upper edge of the bars 86 and force them downward. The lower ends of the
- 25 levers 164 are provided with pins 166 which project through slots 167 in the cheek plates 34 and 35, which slots are of a length equal to the slots 165. The levers 164 are reciprocated up and down by means of levers 168
- 30 arranged adjacent the inner face of the cheek plates 34 and have bifurcated rear ends 169 which straddle the pins 166. The levers 168 are pivoted at 170 to each cheek plate and are oscillated by suitable connecting mechanism driven from a cam on the shaft 74.
- As has been before described, after the printing operation takes place the bar 163 is lowered so as to come in contact with the
- 40 upper edges of the bars 86 and force them downward. At about the same time, the bell crank 139 is operated by the mechanism heretofore described which will lower the lever 132 and disengage the abutment 135 thereof from the cam face 136 formed on the lower edges of the rack bars 82 and permit the rack bars to move forward until the abutments 104 carried thereby, come into engagement with the notch 38 of the
- 45 naught stop 16.
- The means for causing the forward movement of the bars which have been released from the kick back mechanism, comprises levers 181 pivoted to a bar 182 carried by
- 50 the cheek plates 34, the upper end 183 of which is adapted to come in contact with pins 184 carried by rack bars 82, and force them forward by means of a spring 185 which is strained between the lower end of
- 55 the levers 181 and a rod 186 carried by the cheek plates 34. The forward movement of the upper ends of the levers 181 is limited by means of a horizontally disposed comb plate 188. Attention is called to the fact
- 60 that all of the operations heretofore de-

scribed take place during the forward movement of the bars 82 and therefore the movement of the said bars in a forward direction may be termed the printing stroke.

The accumulating elements of the machine are arranged to be operated during the rearward movement of the bars 82, and a description of this mechanism will now be given.

The accumulating mechanism comprises a reciprocating carriage having spaced vertically arranged cheek plates 189 which are arranged within and adjacent to the cheek plates 34 respectively as is shown in Fig. 3. At the lower part of the forward end of the cheek plates 189 is mounted a transverse horizontally extending shaft 192, the outer ends of the shaft 192 projecting through longitudinal slots 193 (Fig. 1) in the cheek plates. Upon the shaft 192 are mounted spacing collars 193 (Fig. 5) which are rigidly held together between the cheek plates 191 by means of collars 194 which clamp against the outside of the cheek plates 191 by means of a nut 195. Revolvingly mounted in each of the spacing collars are gear wheels 197 each having ten gear teeth 198 thereon. One side face of each of the gear wheels 197 is provided with an annular collar 199 (Fig. 3) having on its periphery an abutment or triangular projection 200 providing a radial front face 201 and an inclined cam face 202. The abutment 200 is made on the periphery of the collar 199 so that it lies adjacent gear tooth "0" of the gear teeth 198. The collars 199 are also provided with an abutment 203 having a rounded face and this abutment is arranged adjacent gear tooth "5" and diametrically opposite the abutment 200. The functions of the abutments 200 and 203 will be hereinafter set forth,

The rear end of the cheek plates 189 is provided with longitudinal slots 205 which receive a releasing guide rod 206 rigidly carried by the cheek plates 34.

Means is provided for reciprocating the accumulating carriage backward and forward on the guide rod 206 and the shaft 192 which carries the accumulating gear wheels. This means comprises levers 207 (Fig. 1) which have their upper ends respectively pivoted to the shaft 192. The lower ends of the levers are pivoted to stud shafts 211 on the upper part of levers 215. The lower parts of the levers 215 extend inwardly toward each other and are provided with vertically extending relatively rectangular shaped plates 219 (Figs. 1 and 6) pinned together at their upper and lower edges by means of pins 221. The said plates 219 are provided with registered openings to receive a cam shaft 225, which cam shaft is loosely mounted on a shaft 226 which passes through its center rigidly mounted upon

which are collars 227 which abut against the ends of the cam shaft 225. The collar 227 is provided with an annular groove 228 adapted to receive the bifurcated end 231 of a lever 232 which is pivotally mounted at 233 to the frame work as is shown in Fig. 2.

The base 5 carries the entire type setting and accumulating mechanism and also the reciprocating printing carriage 13. The lever 232 intermediate its end is provided with a rectangular cage 235 within the walls of which is reciprocatably mounted a plunger 238 having a cam engaging head on its upper end. A spring 240 is compressed between the inner face of the said cam engaging head and the wall of the cage. The spring is normally held compressed by means of a bell crank 239 pivoted to the lever 232 one end 241 of which is adapted to engage a collar 242 carried on the inner end of the reciprocating plunger 248. The other arm of the bell crank 239 is provided with a key 243, which upon being pressed, disengages the lever 241 with the collar 242 and permits the plunger to be forced upwardly under action of the spring. The plunger upon being released enters a cam groove in the periphery of a suitable cam on the cam shaft 74. This cam is so shaped that as the cam head runs in said groove the lever 232 will be pushed to one side by the said groove and thereby cause a sidewise movement of the lever 232 which will slide the cam shaft 225, the purpose of which shifting will be hereinafter set forth. As the cam shaft 74 reaches the end of its revolution said cam grooves each terminate in an abutment having an inclined face which will engage the end of the head, the plunger 238 and force it downwardly until the collar 242 slides over an inclined face on the lever 241 and snaps in back of the said lever and is held in its locked position as is shown in Fig. 2. A coil spring 248 strained between the end 45 of the lever 241 and the upper edge of the lever 232 provides means for normally holding said end in an upward position to be engaged by the collar 242.

Returning now to the levers 215, which as stated are for the purpose of reciprocating the accumulating carriage, these levers are pivotally mounted upon a transverse shaft 250 which is mounted in the cheek plates 34. Between the said levers 207 and pivotally mounted on the shaft 250 are contacting-ends 251 of two separate levers 253 and 254 respectively each of which has an opening receiving the cam shaft 225. The outer ends of the levers 253 carry rollers 260 and 261 of which one 260 is shown engaging a cam groove 262, which, during the revolution of the cam shaft 74 transmits a rocking motion to the said lever 253 which through the medium of the levers 213 and 207 reciprocates the accumulating carriage. When the

said accumulating carriage is being reciprocated by the lever 254, the accumulating elements thereof are actuated for accumulating purposes only, and when operated by the other lever 253 the accumulating carriage 70 will be operated for taking totals. Coiled springs 263 are strained between ears 264 carried by the levers 207 and 213 for the purpose of normally holding said levers in alignment. The springs 263 are of such 75 strength that the levers 207 and 213 are for all practical purposes a single lever.

When the cam shaft 225 is slid by the lever 232 to one limit of movement, the lever 254 is locked to the levers 213 and the accumulator carriage is rocked for accumulating items. However, when the cam shaft 225 is moved to its other limit of movement, the other lever 253 is locked to the lever 213 and the carriage is reciprocated for taking 85 totals. The cam grooves 262 being differently designed so that this is accomplished.

The arrangement and operation of the cam shaft 225 and its co-operating parts are described in detail in said co-pending application. 90

In Fig. 2, the position of the parts is such that the accumulating carriage is reciprocated for accumulating; the printing operation has been completed and the parts are 95 set for the free return of the rack bars 82. Before the bars 82 return rearwardly, however, the accumulating carriage will be moved forwardly until the accumulator wheels 197 have been brought in contact 100 with the gear teeth 123 of the type segments. The rearward movement of the bars 82 will then rotate the accumulating gear wheels 197 and the type segments. When the rack bars 82 have reached the limit of 105 their rearward movement, the lever 207 is again rocked to reciprocate the accumulating carriage rearwardly and thereby disengage the accumulating gear wheels with the gear teeth of the type segments, and bring 110 the said accumulating gear wheels into engagement with a transverse bar 272 which is carried by the cheek plates 34 and holds the said accumulating gear wheels against accidental shifting. 115

This reciprocation of the accumulating carriage backward and forward and the engagement and disengagement of the accumulating gear wheels with the gear teeth of the type segments takes place as the bars 82 120 are at rest. However, when any of the accumulating gear wheels have made a complete revolution the inclined wall 202 (Fig. 3) of the abutment 200 carried by the said gear wheel has been brought into engagement with the inclined wall 273 made on the lower end of an L shaped settable lever 275, the said lever is rocked upwardly on its pivot 276 against the action of a coil spring 125 274 strained between the lever 275 and a 130

transverse rod 276 carried between the cheek plates 189. This spring normally holds the lever 275 in a horizontal position as is shown in Fig. 2, the upward movement of the lever 5 being limited by a transverse rod 277' mounted between the cheek plates 189. In its horizontal position, the lever 275 holds a vertically extending lever or pendant link 278 to the limit of its upward movement, the 10 upper edge of the lever 275 engaging a lip 279 carried by the side of the lever 278, which movement is limited by the rod 277' mounted in a longitudinal slot 280 in the end of the lever 278, and holds the said lever 278 in its said upward position against the tension of a coil spring 280' strained between the said lever and a transverse rod 281 carried between the cheek plates 189. A horizontally disposed comb plate 281' is 15 carried between the cheek plates 189 forms guide ways for the vertical extending levers 278. Pivoted to the lower end of the lever 278 at the point 282 is a carrying bar or lever 283, guided in a vertically disposed 20 guide comb plate 284. The other end of the lever 283 is pivotally connected to the lower end of a carrying lever or actuator 285 which is provided with an enlarged slot 286 receiving the transverse shaft 277. The upper end of the lever 285 is shaped to form a lever 287 which extends rearwardly in a relatively horizontal direction and is pivotally mounted upon a transverse rod 289, carried between the cheek plates 34. A coil 25 spring 290 strained between the lever 285 and a transverse rod 291 carried by the cheek plates 189, normally holds the outer end of the lever 287 in a downward position. The said outer end of the lever 287 30 is slidably mounted in a vertically disposed comb plate 292 and carries on its outer end a revolvably mounted roller 294 adapted to engage a stepped cam plate 295 provided with cam surfaces 295' which plate is reciprocated back and forth for lifting the roller 294 and rocking the lever 287 against the tension of the spring 290. The cam plate 295 is disposed between the cheek plates 34 and carries at its side edges rollers 296 35 which are adapted to roll in longitudinal slots 297 (Fig. 1) in the cheek plates 34. The means for reciprocating the cam plate 295 backward and forward comprises levers 298 pivoted to the cam plate at the point 299, and carry on their lower edges 40 rack teeth 300 which mesh with a pinion 301, revolvably mounted upon a shaft 302 slidably mounted in a longitudinal slot 303 in the cheek plates 34. Rollers 304 prevent the upward movement of said levers 298 and 45 keep the rack teeth in engagement with the pinion 301. The pinion 301 is also in mesh with stationary rack bars 305 fastened to the outer face of the cheek plates 34. The shaft 302 is moved backward and 50 forward in a slot 303 by means of a lever 307 which has a bifurcated upper end 308 fulcrumed on stud shafts 309 carried by the cheek plates 34. The lower ends of the levers 307 are bifurcated as at 310 to straddle a transverse shaft 311 reciprocated in parallel slots 312 (Fig. 1) in the frame work 234. The transverse shaft 311 passes through the entire machine and is arranged to receive the levers 313 of each independent unit or zone. Levers 313 arranged on each side of the machine have one end 314 pivotally mounted on the transverse shaft 311 and their other ends provided with a longitudinal slot 315 to receive the main drive shaft 74. This end of each lever 313 is provided with a revolvably mounted roller 318 which is arranged to rotate in a cam groove 319 in the cam 77. As the main shaft 74 is revolved, the stepped cam plate 295 is through 75 the lever connections heretofore described, reciprocated back and forth. Due to the arrangement of the pinion 306 and the rack bars 298 and 305, the movement of the rack bar 298 is in ratio of two to one to the 80 movement of the pinion 306 of the rack bar 305. Returning now to the L shaped lever 275, it will be seen that means is provided for locking the rear end of this lever in a downward position when the vertical portion thereof has been raised by engagement with the abutment 200 carried by the accumulative gear wheels. This means comprises a bell crank detent lever 320 (Fig. 3) pivoted 85 upon a transverse shaft 321 carried by the cheek plates 169. Horizontally disposed comb plates 322 guide these levers during their movement. A coil spring 324 strained between the upper end of the lever 320 and a transverse shaft 325 carried by the cheek plates 189 will normally pull the upper end of the lever 320 forwardly and hold it 90 against the inner end of the lever 275. When the lower end of the lever 275 is raised, as 95 heretofore described, the vertically extending portion 326 thereof will snap within a notch 327 formed in the front edge of the lever 320 and hold the said portion 326 in its downward position. The other arm 328 of the bell crank 320 is adapted to come in contact with the transverse shaft 206 and upon doing so will move the upper end of the lever rearwardly against the tension of the spring 328 releasing the vertically extending portion 326 of the lever 275 from the notch 327 and permit the said lever 275 to occupy its horizontal position under the action of the spring 277. A description of the operation of the carry 100 over mechanism which has just been above described will now be given. After the accumulating gear wheels have made a complete revolution and the abutment 200 thereon comes in contact with the cam face 273 105

110

115

120

125

130

of the vertically extending portion 274 of the lever 275 the said lever will be rocked about its pivot so that its inner end is lowered. The lowering of the inner end of the lever 275 permits the vertically extending rod 278 to be drawn down under action of the spring 280 so that the lever 283 will be dropped down in front of the abutment 104 carried by the reciprocating bars 82. When 5 any one of the accumulating gear wheels have made a complete revolution the reciprocating bar 82 associated therewith will of necessity be in its extreme rearward position. Both the vertically extending lever 278 and the inner end of the lever 275 descend simultaneously, the lever 275 being locked in its downward position by means of the bell crank 320 and the vertical lever 278 being held in its downward position by means 10 of the coil spring 280. When the parts are in the position above described, the reciprocating cam plate 295 is moved forwardly by means of the levers 298, 307 and their associated elements. A forward movement of 15 the cam plate 295 will engage the inclined cam surface 295' thereon with the roller 294 carried by the inner end of the lever 297 thus raising the roller. The lifting of the roller 294 will rock the lever 285 about its pivot 20 288 thereby forcing the lever 283 pivoted thereto in a rearward direction and bringing the inner end of the lever 283 into engagement with the abutment 104 made on the upper edge of the reciprocating bar 82, and 25 force the said bar backward a distance sufficient to turn the gear wheel 120 to oscillate the type segment a distance sufficient to rotate the accumulator gear wheel with which it is associated, back one tooth. It is of 30 course to be understood that due to the fact that the abutments 200 are carried by the left hand face of each accumulative gear wheel, the set back mechanism heretofore described of the next adjacent accumulative 35 gear wheel to the left is actuated. In other words, a rotation of one of the accumulative gear wheels will actuate the set back mechanism of the accumulative gear wheel of the next higher order.

40 A brief description of the entire machine thus far described will now be given explaining the sequence of operation of the various mechanisms to print and accumulate the data perforated in the cards which 45 are passed through the machine.

50 As a card is fed through the machine various stop pins 14 are elevated corresponding with the various perforations of the card. The elevation of the stop pins 14 55 will lower the naught stops 16 in the rows in which the stop pins are elevated. The lowering of the stop pins will permit the reciprocating bars 82 associated therewith, to be moved forwardly. The forward movement of the bars 82 will depress the 60 levers 132 which are associated therewith, and these levers will depress all of the levers 132 to the right thereof which have not been depressed by the forward movement of the reciprocating bars associated therewith. All 65 of the levers 132 however, to the left of the lever 132 which has been depressed by the forward movement of the rack bar will still be in their upright position. While the reciprocating bars 82 which have been released are moving forwardly, these last mentioned levers 132 will be reciprocated rearwardly by means of the bell cranks 139 70 levers 143 and other elements associated therewith, which in their rearward movement will force back the bars 82 with which they are associated, and oscillate the type segments actuated by these rack bars downwardly to a non-print position. The bars 82 move forwardly under the action of the reciprocating bar 89 until the abutments 75 104 carried on their lower edges come in contact with the various elevated stop pins 14 at which time they come to a rest. When 80 the rack bars 82 have come to a rest, the segments associated therewith have been oscillated upwardly a distance sufficient to set the type thereon in consonance with the number of the stop pin 14. When all of 85 the type segments have been oscillated into proper position the detent 130 is drawn down into engagement with the gear teeth 123 on the type segments and alines and locks them so that they cannot be moved during 90 the print operation. Simultaneous with the operation of the detent, the levers 62 and 95 163 are actuated, the former causing the drawing down to the set stop pins 14 and elevating all of the naught stops 16, the latter 100 contacting with the reciprocating bars 86 for lowering them so that on their return movement the bell cranks 97 carried thereby 105 will be in position to rest upon the top of the naught stops 16. The reciprocating printing carriage 13 is then brought into 110 engagement with the type segment and an impression made on the paper carried thereby. The rack bars 82 are now ready for their rearward movement, but previous thereto the reciprocating accumulating carriage has been moved forwardly so that the accumulating gear wheels are brought into engagement with the teeth 123 of the type segments. The locking detent for the type segments is withdrawn and the reciprocating 115 bars are moved rearwardly under action of the bar 89. The rearward movement of the rack bars 82 will revolve the accumulating gear wheel through the medium of the type segments and rotate the gear teeth thereon 120 corresponding with the type printed. When the bars 82 have completed their rearward motion, the reciprocating accumulating carriage is also moved rearwardly so as to disengage the accumulative gear wheel from 125 130

the type segments and to move them into engagement with a transverse bar to lock them against further rotation. All of the elements are now ready for a second forward movement of the reciprocation bars 82, and the above operation continues. When any of the accumulative gear wheels have made a complete revolution, during which time the bars 82 associated therewith have moved rearwardly into naught stop position, the L shaped bars 275 are rocked, which through the mechanism heretofore described, will move the rack bar 82 adjacent to the left thereof, back one space so that the accumulative gear wheel associated with this rack bar will also be moved back one space, and in this way form the "carry over."

The above operation continues as the cards pass through the machine and the items thereon are printed by the type sectors and accumulated on the accumulator wheels until either a total card is fed to the machine or until it is desired to take the total of the data accumulated by operating a total key manually. A description of this total taking mechanism will now be given.

All of the actions heretofore described have taken place when that one of the levers 253, which I might term the accumulating lever, is locked by means of the reciprocating cam shaft to the levers 215. When the total is to be taken the key 240 is lifted either manually or by a push rod A controlled by the perforated cards, as is described in my copending application, Serial No. 80,973, filed Feb. 28, 1916. The reciprocating plunger 238 is released, which will spring into the cam groove as stated and upon engaging therewith will rock the lever 232 about its pivot 233 and reciprocate the cam shaft 255, which will unlock the accumulating lever 254 and lock the total taking lever 253, whereupon the locking of the lever 208 with the other lever 253 which I may term the total taking lever will cause the said lever to reciprocate the accumulating carriage forwardly until the accumulator wheels are brought into contact with the type segments.

At the same time that the cam shaft 255 is reciprocated as above described, means is provided for lowering the pins 14 and the naught stops 16, so that the bars 82 will be in a position to move forward. This means is described in detail in said co-pending application Serial No. 158,142 and need not be described here.

After the accumulator gear wheels have been moved into mesh with the gear teeth on the type segments and after both the naught stops and the stop pins have been lowered as above described, all the elements will have been set to permit a forward movement of the bars 82. The bars 82 are moved for-

ward under the action of the transverse bar 89 and its associated elements, the said bar 89 being gripped between the abutments 104 and the notches 88 formed in the upper edges of the bars 86. The forward movement of the bars 82 rotate the accumulator gear wheels in the direction which is anti-clockwise in Fig. 2, until the radial wall of the abutments 200 come into contact with the rear edges of the vertically extending portion of the bar 275 (Fig. 8). When the accumulating gear wheels have been stopped in the manner heretofore described they have revolved their associated type segments upwardly a distance sufficient to set into printing position the type corresponding with the gear teeth of the accumulating wheels. Since all of the accumulating wheels will not revolve the same distance, but since it is necessary that the bar 89 should move to the limit of its outward movement, means is provided for releasing the said bar from engagement with the notches 88 formed in the bar 86 so that the bar 89 may slide on the upper edge of the bar 86 as is shown in Fig. 26. This means comprises a lever 350 pivoted to a transverse shaft 351 carried by the cheek plates 189 and is provided on its upper edge with a rounded abutment 353 which is adapted to come in contact with the rounded abutment 203 carried on the collar 199. When the said abutment 203 and 353 come in contact as is shown in Fig. 26, the lever 350 is forced downwardly, which will force the bars 86 also downwardly through the medium of an outwardly turned lip 354 formed on the outer end of the lever 350. The forcing down of the bars 86 as before described, will release the transverse reciprocating bar 89 and permit it to move downwardly to the limit of its stroke. When all of the type segments have been set up in the manner heretofore described, the detent 130 is brought into contact with the gear teeth of the type segments and locks the said segments in printing position. The reciprocating printing carriage 13 is then moved up into engagement with the type and an impression made on the paper carried thereby. This impression gives the total of the data accumulated by the accumulative gear wheels. After the printing operation is completed the detent 130 is lifted. The bars 82 then move rearwardly during which motion the reciprocating plunger 238 is forced back into its locked position as shown in Fig. 3, and the lever 232 has been rocked about its pivot 233 and thereby reciprocated the cam shaft 225 back to accumulating position. All of the parts are now in the position to accumulate further data.

It is to be understood that all the description thus far has been given relative to the operation of one unit of the machine, that is, one printing and accumulating section 130

- composed of 9 type sectors and 9 accumulating gear wheels together with their associated and co-operative elements. It is also to be understood, however, that each unit 5 may contain a greater or less number of associated printing and accumulated elements. The complete machine, however, comprises a number of units each identical with the unit heretofore described.
10. If it is desirable to split a column, so that any particular line of digits will neither accumulate or print, means is provided for holding the bars 82, associated with the digits to be kept from printing and accumulating, so that it cannot run forward and backward to set type and accumulate and also to hold the bar 82 back far enough to render the type segment associated therewith to occupy a non-print position. This 15 means comprises a plurality of latch levers 401 (Fig. 2) which are pivotally mounted upon a transverse bar 402 carried between the cheek plates of the machine. When it is desired to render a line of digits inoperative, the reciprocating bar 82 associating therewith is drawn back so that the upper end of the latch lever 401, which is provided with a hook 403 will hook over a horizontally extending pin 404 (Figs. 8 20 and 9) carried by the vertically extending portion 92 carried by the bar 82. This holds the recess 88 and the shoulder formed thereby out of reach of the drive bar 89, whereby the latter may continue to reciprocate 25 without moving the bars 82 and 86.
- The printing carriage, designated generally by reference numeral 13 (Fig. 1) is located on the printer tabulator base, opposite the type 126.
40. The carriage is supported at opposite ends on the cam shaft brackets 599 and the lever shaft brackets 601 carried on the base plate of the printer tabulator.
- The lever shaft brackets 601 are provided 45 at their upper ends with guide slots 604 in which are received the L shaped carriage supporting brackets 605 provided at their forward ends with anti-friction rollers 606 adapted to reciprocate in the elongated 50 openings 607.
- The printing carriage is carried on these L shaped brackets and is reciprocated therewith by means of bell-cranks 610 pivoted on a shaft 611 and provided with a roller 55 engaging in a groove on a suitable cam carried on the cam shaft 74. The carriage is reciprocated so as to bring the paper against type while the type segments are held locked by the detent 130.
60. The printing carriage is described in detail in said first named co-pending application.
- I claim:
1. A printing tabulator mechanism comprising type segments, reciprocating rack bars operatively associated therewith, means for moving the said rack bars to position the said type segments in printing position, a reciprocating accumulating carriage, accumulating elements carried thereby, means 70 for reciprocating the accumulating carriage whereby the accumulating elements are brought into operative connection with the said type segments, and a carry-over mechanism for the accumulating elements carried 75 by the accumulating carriage, said carry-over mechanism adapted to engage the reciprocating rack bars for causing the carry-over operation.
2. A printing tabulator mechanism comprising type segments, reciprocating rack bars operatively associated therewith, means for moving the said rack bars to position the said type segments in printing position, a reciprocating accumulating carriage, accumulating elements carried thereby, means for reciprocating the accumulating carriage whereby the accumulating elements are brought into operative connection with the said type segments, and a carry-over mechanism 80 for the accumulating elements carried by the accumulating carriage, said carry-over mechanism adapted to engage the reciprocating rack bars for causing the carry-over operation, said carry-over mechanism set in operation by the accumulating elements.
3. A printing tabulator mechanism comprising type segments, reciprocating rack bars operatively associated therewith, means for moving the said rack bars to position the said type segments in printing position, a reciprocating accumulating carriage, accumulating elements carried thereby, means for reciprocating the accumulating carriage 85 whereby the accumulating elements are brought into operative connection with the said type segments, and a carry-over mechanism for the accumulating elements carried by the accumulating carriage, said carry-over mechanism adapted to engage the reciprocating rack bars for causing the carry-over operation, said carry-over mechanism set in operation by the accumulating elements.
4. A printing tabulator mechanism comprising a printing mechanism, a tabulating mechanism comprising a reciprocating accumulating carriage, accumulative elements carried thereby, reciprocating members for actuating the accumulative elements, and a carry-over mechanism set in operation by the accumulative elements and engaging the reciprocating members for moving them, said carry-over mechanism comprising rockable levers adapted to engage the reciprocating members, and reciprocating means for operating the rockable levers.

5. A printing tabulator mechanism comprising a printing mechanism, a tabulating mechanism comprising a reciprocatory accumulating carriage, accumulative elements carried thereby, reciprocating members for actuating the accumulative elements, and a carry-over mechanism set in operation by the accumulative elements and engaging the reciprocating members for moving them, said carry-over mechanism comprising rockable levers adapted to engage the reciprocating members and a reciprocating cam plate for operating the rockable levers. 70
- 10 6. A printing tabulator mechanism comprising a printing mechanism, a tabulating mechanism comprising an accumulating carriage, accumulative elements carried thereby, reciprocating members for actuating the accumulative elements, and a carry-over mechanism set in operation by the accumulative elements and engaging the reciprocating members for moving them, said carry-over mechanism comprising rockable levers adapted to engage the reciprocating members and a reciprocating cam plate for positively operating the rockable levers to effect carrying. 80
- 15 7. A printing tabulator mechanism comprising a printing mechanism, a tabulating mechanism comprising an accumulating carriage, accumulative elements carried thereby, reciprocating members for actuating the accumulative elements, a carry-over mechanism set in operation by the accumulative elements and engaging the reciprocating members for moving them, said carry-over mechanism comprising rockable levers adapted to engage the reciprocating members and a reciprocating cam plate for operating the rockable levers, and means for reciprocating the cam plate, said means comprising a cam and a lever operatively connected thereto and to the cam plate. 85
- 20 8. A printing tabulator mechanism comprising a printing mechanism, a tabulating mechanism comprising an accumulating carriage, accumulative elements carried thereby, reciprocating members for actuating the accumulative elements, a carry-over mechanism set in operation by the accumulative elements and engaging the reciprocating members for moving them, said carry-over mechanism comprising rockable levers adapted to engage the reciprocating members and a reciprocating cam plate for operating the rockable levers, and means for reciprocating the cam plate, said means comprising a rack bar carried by the plate, a pinion in mesh therewith and means for sliding the said pinion. 90
- 25 9. A printing tabulator mechanism comprising a printing mechanism, a tabulating mechanism comprising an accumulating carriage, accumulative elements carried thereby, reciprocating members for actuating the accumulative elements, a carry-over mechanism comprising movable levers for engaging the reciprocating members for moving them, and means for normally holding the said movable levers out of engagement with the reciprocating members except during carrying. 95
- 30 10. A printing tabulator mechanism comprising a printing mechanism, a tabulating mechanism comprising a reciprocatory accumulating carriage, accumulative elements carried thereby, reciprocating elements for actuating the accumulative elements, a carry-over mechanism comprising movable levers for engaging the reciprocating members for moving them, and means for normally holding the said movable levers out of engagement with the reciprocating members except during carrying. 100
- 35 11. A printing tabulator mechanism comprising a printing mechanism, a tabulating mechanism comprising a reciprocatory accumulating carriage, accumulative elements carried thereby, reciprocating elements for actuating the accumulative elements, a carry-over mechanism comprising movable levers for engaging the reciprocating members for moving them, and means for normally holding the said movable levers out of engagement with the reciprocating members except during carrying, said holding means comprising a latch lever. 105
- 40 12. A printing tabulator mechanism comprising a printing mechanism, a tabulating mechanism comprising a reciprocatory accumulating carriage, accumulative elements carried thereby, reciprocating elements for actuating the accumulative elements, a carry-over mechanism comprising movable levers for engaging the reciprocating members for moving them, and means for normally holding the said movable levers out of engagement with the reciprocating members except during carrying, said holding means comprising a latch lever adapted to be tripped by engagement with the accumulative elements. 110
- 45 13. A printing tabulator mechanism comprising a printing mechanism, a tabulating mechanism comprising an accumulating carriage, accumulative elements carried thereby, reciprocating elements for actuating the accumulative elements, a carry-over mechanism comprising movable levers for engaging the reciprocating members for moving them, means for normally holding the said movable levers out of engagement with the reciprocating members, said holding means comprising a member for supporting the movable levers, and a latch for holding the supporting member in supporting position. 115
- 50 14. A printing tabulator mechanism comprising a printing mechanism, a tabulating mechanism comprising an accumulating carriage, accumulative elements carried thereby, reciprocating elements for actuating the accumulative elements, a carry-over mechanism comprising movable levers for engaging the reciprocating members for moving them, means for normally holding the said movable levers out of engagement with the reciprocating members, said holding means comprising a member for supporting the movable levers, and a latch for holding the supporting member in supporting position. 120
- 55 15. A printing tabulator mechanism comprising a printing mechanism, a tabulating mechanism comprising an accumulating carriage, accumulative elements carried thereby, reciprocating elements for actuating the accumulative elements, a carry-over mechanism comprising movable levers for engaging the reciprocating members for moving them, means for normally holding the said movable levers out of engagement with the reciprocating members, said holding means comprising a member for supporting the movable levers, and a latch for holding the supporting member in supporting position. 125
- 60 16. A printing tabulator mechanism comprising a printing mechanism, a tabulating mechanism comprising an accumulating carriage, accumulative elements carried thereby, reciprocating members for actuating the accumulative elements, a carry-over mechanism comprising movable levers for engaging the reciprocating members for moving them, means for normally holding the said movable levers out of engagement with the reciprocating members, said holding means comprising a member for supporting the movable levers, and a latch for holding the supporting member in supporting position. 130

14. A printing tabulator mechanism comprising a printing mechanism, a tabulating mechanism comprising an accumulating carriage, accumulative elements carried thereby, 5 reciprocating elements for actuating the accumulative elements, a carry-over mechanism comprising movable levers for engaging the reciprocating members for moving them, means for normally holding the said movable levers out of engagement with the reciprocating members, said holding means comprising a pivoted lever for supporting the movable levers, and a spring latch engaging one end of the pivoted lever for holding it in a supporting position. 10
15. A printing tabulator mechanism comprising a printing mechanism, a tabulating mechanism comprising an accumulative carriage, accumulative elements carried thereby, reciprocating elements for actuating the accumulative elements, a carry-over mechanism comprising movable levers for engaging the reciprocating members for moving them, means for normally holding the said movable levers out of engagement with the reciprocating members, said holding means comprising a pivoted lever for supporting the movable levers, and a spring latch engaging one end of the pivoted lever 15 for holding it in a supporting position, said pivoted lever having its free end adapted to come in engagement with the accumulative elements for tripping the latch and permitting the movable levers to come in contact with the reciprocating members. 20
16. A printing tabulator mechanism comprising a printing mechanism, a tabulating mechanism comprising an accumulating carriage, accumulative elements carried thereby, reciprocating elements for actuating the accumulative elements, a carry-over mechanism comprising movable levers for engaging the reciprocating members for moving them, means for normally holding the said movable levers out of engagement with the reciprocating members, said holding means comprising a pivoted lever for supporting the movable levers, a spring latch engaging one end of the pivoted lever for holding it 25 in a supporting position, said pivoted lever having its free end adapted to come in engagement with the accumulating elements for tripping the latch and permitting the movable levers to come in contact with the reciprocating members, and a reciprocating cam plate for operating the movable levers when they are in contact with the reciprocating members. 30
17. In an apparatus of the character described, the combination of type sectors provided with gear teeth; rack bars operatively connected to the sectors and each provided with an inwardly disposed shoulder; a reciprocatory accumulator carriage; accumu- 35 lator gear wheels carried on said carriage, 65 and meshing with said gear teeth, and each provided at its side with a triangular projection; settable levers fulcrumed on said carriage and each provided with a hooked inner end adapted to be engaged and raised 70 by said projection; detent levers adapted to hold said settable levers in set position, and to release the settable levers when the carriage is reciprocated outwardly; carrying bars connected to the outer ends of the settable levers and adapted when the settable levers are set to engage and kick back said shoulders; carrying levers each having its lower end pivotally connected to the inner end of a carrying bar; and a reciprocatory 75 cam plate provided with cams adapted to engage the outer end of the carrying levers for actuating said carrying bars. 80
18. In an apparatus of the character described, the combination of type sectors provided with gear teeth; a gear wheel secured to each type sector; rack bars meshing with said gear wheels respectively, and each provided with an inwardly disposed shoulder; a reciprocatory accumulator carriage; an 85 accumulator shaft carried by said carriage; accumulator wheels on said shaft and provided with teeth adapted to mesh with said gear teeth of the type sectors; a collar secured to each accumulator wheel and provided with a triangular projection providing a radial face and an inclined forward face; settable levers, one for each accumulator wheel, fulcrumed on said carriage and each provided with a hooked inner end 90 adapted to engage said radial face and to be lifted by said inclined face; detent levers, one for each settable lever, fulcrumed on said carriage and adapted to engage over and to hold in set position said settable 95 levers; a fixed releasing rod adapted to engage said detent levers to cause the release of the settable levers when the carriage is reciprocated outwardly; pendant links engaging said settable levers and adapted to 100 be lowered when the settable levers are set; carrying bars each having its outer end supported by a pendant link and adapted to engage and kick outwardly said shoulders; intermediately fulcrumed carrying levers 105 each having its lower end pivotally connected to the inner end of the carrying bar, and provided at its outer end with a roller; and a reciprocatory cam plate provided with a plurality of stepped cams adapted to engage 110 said rollers. 115
19. In an apparatus of the character described, the combination of an accumulating mechanism comprising a reciprocating carrying cam plate; a reciprocating rack secured to the carrying part; a fixed rack; a pinion spindle; a pinion fixed thereon between said racks and engaging both of the 120

- racks; a drive means loosely embracing said spindle; and means for reciprocating the drive means.
20. In an apparatus of the character described, the combination of a pair of cheek plates; an adding mechanism therebetween having an accumulator comprising a cam plate; means for guiding the cam plate; a reciprocating rack secured to each side edge 10 of the plate; a pinion spindle passed through the cheek plates; pinions thereon meshing with said reciprocating racks; a fixed rack secured to said cheek plate and meshing with said pinions on the side opposite to said reciprocating racks; a spindle drive lever fulcrumed to each cheek plate and provided with a slot receiving said spindle; and means for reciprocating the drive levers.
- 20 21. In an apparatus of the character described, the combination of a pair of cheek plates having guide slots; an adding mechanism therebetween having an accumulating mechanism comprising a reciprocatory cam 25 plate; supporting rollers carried at the side edges of said cam plate and engaging in said guide slot of the cheek plates; a reciprocating rack secured to each of said side edges; a pinion spindle passing through 30 said cheek plates; pinions thereon meshing with the lower edge of said reciprocating rack; a fixed rack secured to said cheek plates and having its upper edge meshing with said pinion; a spindle drive lever fulcrumed on each cheek plate and each provided with a bifurcated upper end receiving 35 said spindle, and with a lower bifurcated end; a drive spindle engaging in said lower bifurcated end; a cam provided with a carrying groove; reciprocating drive links secured to said drive spindle and each provided with a slot receiving said cam shaft and with a roller engaging in said carrying 40 grooves; and slide ways on which the outer 45 ends of said drive links rest.
22. In an apparatus of the character described, the combination of an adding mechanism comprising a plurality of reciprocating members and a carrying mechanism 50 adapted to positively kick back one or more of said members; and a reciprocating restoring member for restoring said reciprocating members after they have been kicked back.
23. In an apparatus of the character described, the combination of an adding mechanism comprising actuating bars and a carrying mechanism adapted to positively kick back one or more of said bars when carrying is effected; and a spring pressed restoring 55 60 slide slidably mounted to engage each bar and adapted to yieldably hold said bar inwardly.
24. In an apparatus of the character described, the combination of accumulator elements; settable members adapted to be set 65 by the accumulator elements; a carrying member operatively connected to the settable member and movable independently thereof and adapted when the settable member is set to be moved to position for moving said accumulator element to effect carrying; carrying levers connected to said carrying members; and means adapted successively to engage said carrying levers for causing the carrying members to effect carrying. 70 75
25. In an apparatus of the character described, the combination of accumulator wheels; adding elements operatively connected to the accumulator wheels and each provided with a shoulder; settable levers 80 adapted to be set by the accumulator wheels; a carrying bar operatively connected to the settable lever and movable independently thereof and adapted when the settable lever is set to be in position to engage said shoulder; carrying levers connected to said carrying bars; and cams adapted successively to engage said carrying levers for causing the carrying bars to engage said shoulder for effecting carrying. 85 90
26. In an apparatus of the character described, the combination of accumulator gear wheels; adding elements operatively connected to the accumulator gear wheels and provided with a shoulder; carrying levers; 95 settable levers adapted to be set by the accumulator wheels; a carrying bar operatively connected to the carrying levers and settable lever and movable independently of the carrying levers and adapted when the settable lever is set to be in position to engage said shoulder; and cams adapted successively to engage said carrying levers for causing the carrying bars to engage said shoulder for effecting carrying. 100 105
27. In an apparatus of the character described, the combination of accumulator gear wheels; adding elements operatively connected to the accumulator gear wheels and provided with a shoulder; settable levers 110 adapted to be set by the accumulator wheels; a carrying bar operatively connected to the settable lever and adapted when the settable lever is set to be in position to engage said shoulder; carrying levers connected to said carrying bars; and a reciprocating cam plate provided with cams adapted successively to engage said carrying levers for causing the carrying bars to engage said shoulder for effecting carrying. 115 120
28. In an apparatus of the character described, the combination of accumulator elements; carrying members adapted to be set by said elements into position to actuate the element of the next higher order to effect carrying; a cam member provided with cams adapted to actuate said carrying members for effecting carrying; and means separate from said cam plate for restoring said settable members. 125 130

29. In an apparatus of the character described, the combination of a reciprocatory accumulator carriage; accumulator gear wheels carried on said carriage; adding elements operatively connected to the accumulator gear wheels and provided with a shoulder; settable levers fulcrumed on said carriage and adapted to be set by the accumulator wheels; a carrying bar operatively connected to the settable lever and adapted when the settable lever is set to be in position to engage said shoulder; carrying levers connected to said carrying bars; cams adapted successively to engage said carrying levers for causing the carrying bars to engage said shoulder for effecting carrying; and means movable independently of said cams for restoring said adding elements. 30
30. In an apparatus of the character described, the combination of a movable accumulator carriage; accumulator elements thereon; settable members on said carriage and adapted to be set by the accumulator elements; latches on the carriage for holding the settable members set; a carrying member 35
- operatively connected to the settable lever and adapted when the settable member is set to be in position to actuate the element of the next higher order to effect carrying; and stationary means for positively releasing 30 said latches. 35
31. In an apparatus of the character described, the combination of a reciprocatory accumulator carriage; accumulator gear wheels carried on said carriage; adding elements operatively connected to the accumulator gear wheels and provided with a shoulder; settable levers fulcrumed on said carriage and adapted to be set by the accumulator wheels; latches for holding the settable levers set; a carrying bar operatively connected to the settable lever and adapted when the settable lever is set to be in position to engage said shoulder; and stationary means for positively releasing said latches. 40 45
